UNITED STATES PATENT OFFICE.

WALTER J. SPIRO, OF WHITE PLAINS, NEW YORK.

DESIGN FOR A RUNNING-BOARD MOLDING.

54,285.

Specification for Design.

Patented Dec. 9, 1919.

Application filed June 24, 1919. Serial No. 306,485. Term of patent 7 years.

To all whom it may concern:

Be it known that I, WALTER J. SPIRO, a citizen of the United States, residing at White Plains, in the county of Westchester and State of New York, have invented a new, original, and ornamental Design for a Running-Board Molding, of which the following is a specification, reference being had to the accompanying drawing, forming part thereof.

The figure is a perspective of a running board molding, looking from one end thereof, and showing my new design.

I claim—

The ornamental design for a running board molding, substantially as shown.

WALTER J. SPIRO.
